United States Patent

Des. 241,936
Patented Oct. 19, 1976

241,936

FILTER UNIT

Nils O. Rosaen, 3774 Quarton Road,
Bloomfield Hills, Mich. 48013

Filed Mar. 31, 1975, Ser. No. 563,857

Term of patent 14 years

Int. Cl. D23—01

U.S. Cl. D23—4

FIG. 1 is a perspective view of a filter unit showing my new design;

FIG. 2 is a top plan view;

FIG. 3 is a bottom plan view, a portion of the handle being omitted for convenience of illustration;

FIG. 4 is a front elevational view;

FIG. 5 is a side elevational view; and

FIG. 6 is a rear elevational view.

I claim:

The ornamental design for a filter unit, as shown.
